FIG. 1 is a front perspective view illustrating my design for a monster body pillow;

FIG. 2 is a front view thereof;

FIG. 3 is a right side view thereof;

FIG. 4 is a left side view thereof;

FIG. 5 is a top view thereof;

FIG. 6 is a bottom view thereof;

FIG. 7 is a rear view thereof;

FIG. 8 is a rear perspective view; and,

FIGS. 9-13 are front views showing the pillow in alternate environments of my design for a monster body pillow.

The broken line disclosures in FIGS. 1-2 and 9-13 are for illustrative purposes only and form no part of the claimed design.
